UNITED STATES PATENT OFFICE

2,638,936

METHOD AND MEANS FOR AUTOMATICALLY
WINDING FILLING BOBBINS IN A LOOM
AND SUPPLYING THEM TO THE SHUTTLE
THEREOF

William V. Goodhue and Robert E. Morton, Warwick, R. I., assignors to Universal Winding Company, Boston, Mass., a corporation of Massachusetts

Application May 3, 1950, Serial No. 159,814

32 Claims. (Cl. 139—224)

1

This invention relates to a method and means for automatically winding filling bobbins in a loom and continuously supplying them for transfer to the shuttle or shuttles of the loom.

More specifically, the invention consists in providing automatically-operated bobbin-winding means incorporated in the loom and operative in synchrony with the weaving mechanism thereof to wind filling-bobbins in series, doff the wound bobbins from the winding means and furnish them to the magazine of the loom for transfer to the shuttle as called for by the weft-replenishing or filling-changing means.

One object of the invention is to provide in a loom, bobbin-winding means, means for operating said winding means automatically to don empty bobbins in connection with a rotary winding spindle, means for traversing yarn on the bobbins, means for doffing each bobbin as the winding is completed, means to deliver the wound bobbins to a reserve magazine, and means for drawing out a length of yarn or "transfer-tail" from each doffed bobbin and holding it under tension extended from the reserve magazine, and finally shifting the transfer-tail into alignment with the eye of the shuttle to thread the latter as the bobbin is inserted thereinto by the transfer means.

Another object is to provide means for receiving spent bobbins ejected from the shuttle, holding them and removing the residue of yarn therefrom, conveying the denuded or empty bobbins back to the winding means, and depositing them into a magazine from which they are applied individually to the winding spindle by the donning mechanism.

Another object is to provide means for synchronizing the operation of the winding means with that of the loom to continuously maintain a supply of wound bobbins in reserve for transfer to the shuttle as the yarn in the service winding on the running bobbin is exhausted.

Another object is to provide means in the reserve magazine actuated automatically by the bobbins transferred thereto to arrest the operation of the winding means when said magazine is filled with reserve bobbins.

Another object is to provide means for restarting the winding operation after the number of reserve bobbins in the loom-magazine has been reduced by a bobbin transfer.

Another object is to provide for the automatic operation of the several mechanisms in synchrony with that of the loom to insure a continuous supply of wound filling-bobbins therefor.

2

Further objects and advantages of the invention are set forth in the following specification which describes a preferred form of construction of the loom and its cooperating bobbin-winding and supplying means as illustrated by the accompanying drawings. In the drawings:

Fig. 1 is a front elevation of a portion of an automatic loom showing the filling-changing mechanism thereof, the bobbin-winding means, the means for continuously supplying wound bobbins to the reserve magazine for transfer to the shuttle of the loom, and the means for stripping the residue of yarn from doffed bobbins and conveying them to the magazine for the winding means;

Fig. 2 is a partial end view of the loom showing the connections between the weaving mechanism and the bobbin-winding and furnishing means;

Fig. 3 is an enlarged front view of the end portion of the loom illustrating the winding means with its donning-and-doffing mechanism, the conveyor-means for transporting empty bobbins to the magazine therefor and depositing them therewith, the loom-magazine for holding reserve bobbins and certain other elements of the mechanism;

Fig. 4 is a similar enlarged view of the winding means showing the traveling clip or retriever for taking the yarn from the end of a wound bobbin, carrying it back along a newly donned empty bobbin and attaching it thereto to start the winding operation; and also illustrating the cooperating clip which takes the end trailing from the doffed bobbin, severs it from the supply end and carries it to the tensioning drum as the wound bobbin is delivered to the reserve-bobbin magazine in the loom;

Fig. 5 is a still further enlarged view of the winding means illustrating the upper traveling clip or retriever as having returned the yarn-guide to initial winding position with the yarn attached to an empty bobbin and the lower clip as moved into position to engage the trailing yarn from the doffed bobbin with the teeth of the comb at the top of the tensioning drum;

Fig. 6 is an enlarged front view of the magazine for reserve bobbins and the rotary drum for winding on the transfer-tails of yarn extending from the bobbins held therein;

Fig. 7 is a part-sectional end view of the winding means in slightly reduced scale showing the magazine for empty bobbins, the bobbin-donning means, the bunch-winding means; and also a portion of the magazine for wound bobbins with its operating mechanism;

Fig. 8 is a rear elevational view of the winding means looking in a direction opposite from that of Fig. 4 and illustrating the means for traveling the retriever-clip to return the yarn to the butt end of the empty bobbin and attach it thereto; and also traveling the cooperating clip for taking the trailing end from the doffed bobbin, severing it and carrying it to the tensioning drum;

Fig. 9 is an enlarged rear elevational view of the clip-operating means showing the winding-on drum, its rotating means and also the reserve-bobbin magazine control-mechanism for arresting the operation of the winding means when said magazine becomes temporarily filled with bobbins;

Fig. 10 is an enlarged top plan view of the tensioning drum showing the ratchet-means for rotating it in dotted lines;

Fig. 11 is an enlarged elevational view of the lower portion of the drum showing the means for rotating it and other details;

Fig. 12 is a greatly enlarged elevational view of the two cooperating yarn-clips indicating the connection between the upper clip or retriever and the yarn-guide for returning the guide to initial winding position;

Fig. 13 is a plan view of the same showing the latching means which connects the retriever-clip with the yarn-guide and also illustrating the bunch-winding means and the swinging bail which cooperates therewith for partially wrapping the yarn around the barrel of the bobbin to insure its engagement in under the prongs of the ferrule by which it is attached to the bobbin;

Fig. 14 is a plan view of the upper yarn-clip or retriever;

Fig. 15 is a plan view of the lower clip;

Fig. 16 is a view showing the upper portion of the tensioning drum, the clip for carrying the end of the yarn thereto, the yarn-trap for retaining the end of the yarn above the drum to insure its proper engagement therewith, and illustrating the clip as passing under the gripping means of the yarn-trap;

Fig. 17 is a similar view showing the gripping means of the yarn-trap released by the clip to retain the end of the yarn as the clip is returned from the end of its travel;

Fig. 18 is a rear elevational view of the yarn-trap showing the spring for actuating the gripping element;

Fig. 19 is a part-sectional detail view of the tension-control means for relieving the tension on the yarn at the start of winding a bobbin;

Fig. 20 is a side view of the yarn-clamp for taking the end of a transfer tail from the bottom of the tensioning drum and carrying it into alignment with the eye of the shuttle; and

Fig. 21 is a detail view of the operating mechanism for the yarn-clamp.

In the production of various kinds of fabrics in textile mills the cloth is woven on looms located in a weave-room and the weft or filling-yarn is supplied thereto on bobbins prepared in a separate department such as a winding room. With such previously-used practice the winding machines must be tended by operatives and the bobbins handled and transported to the weave-room for manual application to the loom-magazines or batteries. By use of the present invention, which provides means for winding the filling-bobbins in the loom and furnishing them directly to a reserve magazine or battery for transfer to the shuttle, the winding room is elim-

inated, thus effecting a very considerable saving in floor-space, cost of light and heat, upkeep, etc., besides materially reducing labor charges. It will thus be observed that the present invention assumes great importance as its use results in manifold economies to reduce the cost of weaving various kinds of fabric on broad looms.

General organization

Referring to the present drawings, Fig. 1 illustrates a portion of an automatic loom at the filling-changing end, showing the automatically-operated bobbin-winding means, including bobbin donning-and-doffing mechanism, and the various other instrumentalities for furnishing weft or filling-bobbins to the shuttle or shuttles of the loom. Also illustrated in Fig. 1 is a "bobbin-stripper," so-called, for receiving spent bobbins ejected from the loom-shuttle, removing the residue of yarn usually remaining thereon in the bunch or reserve winding, and conveying the stripped or denuded bobbins back to the magazine of the winding means for donning them thereon in connection with the rotary winding spindle. One preferred type of such a bobbin-stripper is illustrated and described in our prior application for United States Letters Patent, Serial No. 112,362, filed August 25, 1949. The loom may be of conventional type as regards its general organization with its automatic filling-changing mechanism modified as required for cooperation with the bobbin-winding means; and the automatic winding means may be of a type such as shown in United States Letters Patents Nos. 2,257,651 and 2,302,715. The loom may comprise the usual reciprocating lay 2, shuttle 5 received in the box 6 at the end of the lay, the picker-stick 7 for driving the shuttle from this end of the loom, and the various other instrumentalities generally employed in automatic looms. The automatic filling-changing means for transferring fresh bobbins to the shuttle is described more in detail hereinafter in connection with the bobbin-winding and furnishing means.

Bobbin-winding means

As herein illustrated, the winding mechanism is incorporated in the frame 4 of the loom and located above the filling-changing mechanism with its driving means enclosed in a housing or casing 8 and driven by an electric motor 9, also enclosed in the casing. The winding spindle 10 projects from one end of the casing 8 and carries a recessed driving-center or spindle-cup 11 for receiving the head *h* of the bobbin *b* as shown in Figs. 4 and 5. The tip end of the bobbin *b* is likewise supported in the recess of a rotatable center 12 at the end of a stub-spindle or slideable plunger 13 held in an outboard bearing 15, similar to the tail-stock of a lathe. The outboard bearing 15 is shiftable to retract the outer spindle-center 12 and release a wound bobbin for doffing it from the winding spindle 10; the instrumentalities for effecting the doffing operation being described more in detail hereinafter.

Empty bobbin magazine

Mounted above the winding means is a magazine 20 for containing empty bobbins *b*, which may be of wood or other material in conventional shape with an enlarged head *h* at one end and a barrel tapering towards its opposite tip end. Preferably, bobbins of a type such as shown in an application for United States Letters Patent Serial No. 76,365, filed February 14, 1949,

now Patent No. 2,614,771, dated October 21, 1952, are employed for the present purpose. In accordance with the disclosure in said application, the wooden bobbin *b* shown herein is provided with a metal ferrule *f* surrounding its barrel adjacent the head *h* and serrated at its end to form fingers or prongs *p* for catching a strand of yarn slid along the barrel and engaging it thereunder to attach the end to the bobbin prior to starting the winding operation. The method of attaching the yarn to this type of bobbin is illustrated and described in detail in the patent application referred to above and will be explained later herein with reference to the method of operation of the complete apparatus.

The empty bobbins *b* are conveyed from the stripper *S* and deposited in the magazine *20* above the winding means in the manner as later explained. The magazine *20* comprises a pair of vertical chutes *21* and *22* connected at the top by an inclined trough or slideway *19* constituted by spaced side rails. The bobbins are deposited in the trough *19* to cause them to slide therealong for positioning their heads to drop down in the chute *21* with their tip ends guided in the chute *22*. Beneath the magazine *20* are pivoted arms or levers *23* and *24* carrying gripping means for grasping a bobbin from the magazine and carrying it down into position for engagement with the driving-center *11* on the winding spindle *10* and the outer spindle-center *12* as required for donning the bobbin to wind the yarn thereon.

Yarn-traversing means

The filling-yarn *y* is distributed on the bobbins *b* by means of a yarn-guide *25* which is traversed longitudinally thereof with a relatively short stroke by means of a reciprocating traverse-bar *26*. At the start of winding a new bobbin the yarn is retrieved from the outer end of the completed bobbin and carried back to attach the end to the next donned empty bobbin. During this operation the yarn *y* is engaged with a bunch-winding device, indicated generally at *27* in Fig. 4, and described later, which holds it to restrict its traverse and wind a "bunch" of reserve yarn adjacent the head *h* of the bobbin with the coils overlying the ferrule *f*. Upon completion of the bunch-winding the yarn is released from the element *27* and traversed by the guide *25* to build the service winding on the bobbin; the guide being fed progressively outward along the barrel of the bobbin *b* by advancing the traverse-bar *26* through the operation of suitable means enclosed in the casing *8*. In this way the layers of yarn are deposited on the wooden bobbin in conical or tapered chases which build up to form the bobbin with a cylindrical body and tapering tip-end in the manner usually accomplished in filling-winding machines.

Referring to Figs. 3 and 5, the yarn-guide *25* is fast on the end of the slideable traverse-bar *26* which is reciprocated by means as usually provided; for example, a cam and rocker-arm enclosed in the casing *8*. The means for advancing the yarn-guide *25* outwardly along the barrel of the bobbin *b* may consist in a nut engaging eccentric screw-threads on the bar *26* and rotated by suitable means in the casing *8*. As the guide reaches a position adjacent the end of the bobbin *b*, an inclined cam-shaped projection *28* therein, shown by full lines in Fig. 9 and dotted lines in Fig. 5, engages beneath a

trip-element *30* fast on a control rod *31* rotatably held in bearings in the framework of the winding mechanism. This causes the control rod *31* to be rocked to release latching or detent-means for energizing the means for operating the donning and doffing mechanism of the winding means in a manner substantially the same as described in the two patents referred to above. This last referred-to means then operates in a cycle to perform the several functions later explained.

Bobbin-doffing means

The outboard bearing or tail-stock *15* is fastened to a rod or bar *34* reaching back into the casing *8* with its end connected to a lever operated by a cam for sliding the rod to move the outboard-bearing *15* toward the left and engage the spindle-center *12* with the bobbin, see Fig. 5, as shown and described more in detail in a continuing application to be filed later. As shown in Fig. 5, the outboard bearing *15* holds a cylinder *35* in which is slidably mounted the plunger-spindle *13* carrying the rotatable spindle-center *12* with its recessed end receiving the tip end of the bobbin *b* to mount the latter in connection with the driving-center *11* on the winding spindle *10*. A helical spring *37* surrounding the plunger-spindle *13* acts to maintain the spindle-center *12* in engagement with the tip end of the bobbin *b* to hold its head *h* drivingly engaged with the spindle-center *11* when the bearing *15* is moved back toward the casing *8*. The pressure of the spring *37* acts through the spindle-center *11* and bobbin *b* to maintain the latter against the driving-center *11* and hold the spindle connected to its drive. Suitable clutch-members within the casing *8* connect the spindle *10* to its driving means, one clutch-element on the spindle being adapted to be disengaged by a spring as usually provided. A spring *38* on the rod *34*, see Figs. 5 and 9, is compressed and loaded when the outboard bearing *15* is moved toward the casing *8* to don an empty bobbin, means being provided for latching the rod *34* against the force of the spring to retain the bearing in operative relationship. The latching means is released at the completion of winding each bobbin to cause the spring *38* to slide the rod *34* and move the bearing *15* to the right to doff the wound bobbin.

The operation of the means described above moves the outboard bearing *15* to retract the spindle-center *12* and release the bobbin to doff it from winding position and allow it to drop down into the loom-magazine for reserve bobbins in the manner as later explained. It will also be understood that when the bobbin is doffed by retracting the spindle-center *12* pressure on the driving-center *11* will be relieved to thereby permit it to slide to the right as viewed in Figs. 5 and 8 to disengage the clutch-members and disconnect the drive for the spindle *10* to arrest its rotation. Means are provided for arresting the rotation of the winding spindle *10* when it is required to piece up a broken end of yarn. A drop-wire, later described herein, is suspended by the delivering yarn and caused to fall when the yarn breaks to actuate the stopping means in a manner as usually provided.

Bobbin-donning means

Means in the casing *8* operates to rotate a rod *49* carrying the arms *23* and *24*, see Figs. 5 and 7, to swing said arms forwardly and downwardly 75 whereby to carry an empty bobbin *b* down into

axial alignment with the spindle-centers 11 and 12 for engagement therewith. At this juncture the outboard bearing 15 is slid forwardly towards the casing 8 to engage the tip end of the bobbin b with the outer spindle-center 12 and shift the bobbin axially in the same direction to carry its head h into engagement with the driving spindle-center 11. During this operation of donning an empty bobbin the winding spindle 10 is at rest, its rotation having been arrested by the disengagement of the clutch-means described above, but as an empty bobbin is donned between the spindle-centers the movement of the outboard bearing to the left will effect reengagement of the clutch-means to restart the rotation of the 15 spindle.

Yarn tension-control

The filling yarn y may be supplied from any suitable source which is shown in Fig. 1 as a conical package P mounted on a spindle or holder projecting above a shelf 41 upon a column 42 supported from the floor at the end of the loom. The yarn y leads upwardly from the supply-cone P and feeds through a tension-device 43 comprising a plurality of cooperating disks 44 and 45 rotatable about vertical spindles 46. From the tension-device 43 the yarn leads through a guide-eye 47 and thence is drawn down to deliver through an eye 48 in the yarn-guide 25 for attachment to the empty bobbin b. In order that the yarn may not be stretched, strained or broken when taken up suddenly by the initial rotation of the bobbin b, means are provided for relieving the tension thereon at the start of the winding; such a form of tension-control being shown in United States Letters Patent No. 2,236,459 of March 25, 1941, as operated from the winding machine by magnetic means. In the present form of construction the tension-control is operated mechanically by means actuated from the rod 40 which rotates the arms 23 and 24 for donning the bobbins in connection with the winding spindle. As shown in Fig. 5, the end of the rod 40 carries a small beveled pinion 50 meshing with a larger gear 51 on a shaft 52. The gear 51 carries a pin 49 in its hub projecting upwardly therefrom for engagement with a lug on one arm of a bell-crank lever 53. This arm of the lever 53 is connected to a rod 54 slidable in a bearing 55 formed in the framework above the loom. The upper end of the rod 54 is connected to a Bowden wire 56 which is slidable in a flexible tube 57 reaching upwardly to the tension-device 43. Referring to the detailed view, Fig. 19, the upper end of the Bowden wire 56 is connected to a rockable lever 58 which is pivotally mounted on a bracket 59 supported on the mounting for the tension-disks 44 and 45. A helical spring 60 surrounds the wire 56 between a fixed arm 61 depending from the bracket 59 and the end of the downwardly-extending arm 62 of the lever 58 and normally tends to restrain the latter against the pull of the wire. The lever 58 has a portion 63 extending alongside the tension-disks with inclined fingers 64 reaching laterally therefrom for engagement under the rims of the upper tension-disks 44. When the Bowden wire 56 is drawn downwardly by the operation of the lever 53 it acts to rock the lever 58 to raise the fingers 64 and thereby lift the upper tension-disks 44 free from the lower disks 45 to relieve the tension on the yarn feeding between the disks. After the bobbin b starts to rotate and winds on a few coils the rod 40 is turned in the opposite direction to return the arms 23 and 24 to first position. This rotates the pinion 50 and 75

turns the gear 51 to release the pin 49 from the lever 53 so that the tension-control lever 58 is rocked by the spring 60 to remove its fingers 64 from under the tension-disks 44. The tension-disks 44 thus are returned into cooperative relation with the disks 45 to apply the prescribed amount of tension to the delivering yarn y.

The tension-control is also operated during each doffing cycle by means later described to release the yarn so that the wound bobbin is free to drop into the magazine without being restricted by its trailing end before it is severed from the supply yarn. As the yarn y feeds downwardly from the tension-device 43 it draws across an inverted U-shaped thread-bail 70 in the nature of a drop-wire. The bail 70 is pivoted to rotate when released by a break in the yarn to actuate the stopping mechanism in a manner as usually provided in winding machines.

Manually-operative starting means

To start the rotation of the winding spindle 10 after piecing up a broken yarn the outboard bearing 15 must be moved to the left and this may be accomplished manually through the means of a hand-lever 71 shown in Fig. 5. The hand-lever 71 is pivotally mounted in a box-like bearing at the right-hand end of the framework and carries a rotary spindle 72 projecting downwardly therefrom. The spindle 72 is surrounded by a helical spring 73 held under tension to normally maintain the lever 71 in a forward position. On the lower end of the spindle 72 is a cam-piece 74 which is engageable with the end of a slidable pin 75. The end of the pin 75 is adapted to engage the end of a stud 76 projecting from the rearward end of the outboard bearing 15 whereby when the hand-lever is pressed rearwardly it will rotate the cam-member 74 to force the pin against the stud and shift the outboard bearing 15 forwardly into operative position. This means for moving the outboard bearing into operative position can also be employed when the winding is first started and the bobbin is inserted into place between the spindle-centers; it being understood that the plunger-spindle 13 with its center 12 may be forced back sufficiently against the tension of the spring 37 as the tip of the bobbin is placed therein to permit the head of the bobbin to be inserted in the recess in the driving-center 11.

Referring to Fig. 5, the relief of tension on the yarn as the wound bobbin is dropped into the magazine is accomplished by the shifting of the outboard bearing 15 to the right during the doffing cycle. An elbow-shaped lever 77 is pivoted on a screw 78 fastened to the bottom of the box-like opening in the framework which encloses the gears 50 and 51 and the bell-crank lever 53. A pin 79 held in a boss on the side of the outboard bearing 15, see dotted lines in Fig. 5, is adapted to strike against a depending portion of one arm of the lever 77 to rock the latter in contraclockwise direction when the bearing 15 is moved toward the right as viewed in Fig. 5. This causes the opposite horizontal arm of the lever 77 to engage the lower arm of the bell-crank lever 53, whereby to rock the latter to draw the Bowden wire 56 and operate the lever 58 to lift the upper tension-disks 44 and relieve the tension on the yarn for starting the winding. It will be understood that the spring 60, see Fig. 19, normally tends to rock the tension-control lever 58 to release the fingers 64 from the tension-disks when the pull on the wire 56 is released so that they will apply the prescribed

amount of tension to the yarn as it feeds to the bobbin after the winding is started.

Yarn-retriever and transfer-tail clip

It has been stated that in starting to wind on a newly-donned bobbin the yarn is fastened thereto by sliding it under the prongs or fingers *p* on the ferrule *f* surrounding the barrel of the bobbin. It has also been indicated that the yarn trailing from the doffed bobbin is severed and its end carried outward to a tensioning drum for holding it extended from the bobbin when the latter is transferred to the reserve magazine of the loom. The means for performing these several functions consists in a pair of slidable clips *83* and *84* arranged to travel first in one direction and then in the opposite direction in different parallel courses below the winding bobbin. The clips *83* and *84* are shown in detail in Figs. 14 and 15 and the means for sliding them in horizontal paths is illustrated in Fig. 9. A sort of rolling trolley is employed for this purpose, a reciprocable bar *85* moved from a lever *86* in the casing *8* being connected to a carriage *87*, on which are journaled two pairs of spur-gears. The lever *86* may be actuated by a crank-motion in the casing *8* as shown by dotted lines in Fig. 8 and indicated generally by the reference character *88*. One pair of gears is constituted by a pinion *89* connected to a larger gear *90*, arranged with the teeth of the pinion engaging the teeth on a fixed rack *91*. The larger gear *90* of the pair has its teeth in mesh with a rack bar *92* which is connected to the upper yarn-clip *83* for sliding it. The other pair of gears comprises a pinion *95* arranged with its teeth in mesh with those of a fixed rack *91* and connected to a larger gear *97* meshing with a rack bar *94* which is fastened to the lower clip *83* for sliding it. Through this arrangement the motion transmitted to the rod *85* is multiplied to slide the two rack-bars *92* and *94* with an augmented length of traverse so as to travel the clips in opposite directions at accelerated rates of speed in the manner and for the purpose as more particularly pointed out herein-after.

Referring to Figs. 14 and 15, the two clips *83* and *84* are of substantially the same construction and arrangement but reversed in position with the reentrant openings between their jaws facing in opposite directions. As shown in Fig. 14, the upper clip *83*, called the retriever, consists in a rectangular mounting *100* of U-shape having a fixed jaw *101* formed by one of its depending side walls which is flared outwardly at its end. A movable jaw *102* of similar shape is loosely mounted on horizontal studs *103* and *104* projecting through the sides of the mounting *100* to adapt this jaw to rock toward the fixed jaw *101*. A helical spring *105* coiled around the stud *103* acts to force the movable jaw *102* toward the fixed jaw *101* to clamp the yarn therebetween as it is entered between the flaring ends of the jaws. A cam-member *106* is slidably held on the under side of the mounting *100* by means of studs *107* and *108* projecting through slots *109* and *110* in said member. The slot *109* at the forward end of the cam-member *106* is of angular shape to cause this end of the member to be swung laterally as it is slid forward on the mounting *100*. The cam-member *106* has a finger *112* projecting forwardly from its slotted portion and adapted to engage with a lug *113* depending from the outer end of the movable jaw *102* to cam said jaw away from the fixed jaw *101*. Nuts *114* on the ends of

the studs *107* and *108* are set up against the ends of a spring *115* which is formed with a central bowed portion bearing against the under face of the cam-member *106* to hold it in place and apply a slight friction to its sliding motion. The cam-member *106* slides against a plate *116* fastened to the under side of the mounting *100*, the forward end of this plate being beveled on one side to coat with the edge of the forward finger *112* of the cam-member *106* during cooperation of the flaring ends of the jaws *101* and *102*. The edges of the beveled end of the plate *116* and the finger *112* on the cam-member *106* are sharpened, as regards the construction of the clip *84*, for cooperation in the manner of knives or shears to cut the length of yarn held between the jaws *101* and *102* as later explained. On the other hand, in the arrangement of the clip *83* the cam-member *106* overlies the upper face of the plate *116* with a clearance therebetween so that these parts do not act as shears. The clip *83* carries a blade-like element *117* fastened to the inner face of the depending side of the mounting *100* and formed at its forward end with an arcuate extension *118* employed for a purpose later explained.

As before noted, the clip *84* is of substantially the same construction and arrangement as that of the clip *83* and corresponding parts are referred to in the drawings by the same reference characters. As shown in Figs. 15 and 16, the clip *84* is provided with means for opening its jaws *101* and *102* without sliding the cam-member *106*. For this purpose a cylindrical cam *120* is mounted to rotate on the stud *104*. The end of the cam *120* is formed helically so that as it is turned on the stud *104* it will act against the rearward end of the movable jaw *102* to rock the latter; this end of the jaw being formed at an angle to its main portion to provide for the rocking action. A pin *121* projects radially from the cam *120* for rotating it to open the jaws *101* and *102* of the clip *84* at the end of its travel whereby to release the yarn therefrom after it is clamped above the rotary tensioning drum described later. The pin *121* strikes against a fixed abutment *126*, see Fig. 5, which acts to rotate the cam *120* to open the jaws of the clip *84* at the end of its travel.

Referring to Figs. 5, 7, 12 and 13, the two clips *83* and *84* are operated during the doffing of the wound bobbin and the donning of an empty bobbin in the manner as next explained. The clips slide in grooves *122* and *123* in the base of the framework of the winding mechanism, being moved toward and away from each other by the travel of the rolling carriage *87* under the operation of the crank-motion *88* previously mentioned. As the clips *83* and *84* meet and pass each other they continue their motion to engage the yarn trailing from the doffed bobbin and cause it to enter between their jaws. The yarn is entered between the flaring ends of the jaws *101* and *102* which are then closed together to clamp and hold the yarn. The closing of the jaws of the two clips is effected by sliding the cam-members *106* to cause them to release the movable jaw *102* on each clip and permit the spring *105* to force it against the fixed jaw *101*. This sliding motion of the cam-members *106* is caused by their engagement with the beveled ends of a pair of rails *124* and *125* extending horizontally along the base of the framework, see Figs. 5, 14 and 15. As shown in Figs. 14 and 15, the cam-members *106* have rounded side portions *111* adjacent their forward ends which engage against the beveled

ends of the rails 124 and 125 to slide the members rearwardly on the clips 83 and 84. As the cam-members 106 are slid in this manner they are rocked laterally to release the movable jaws 102 of the clips for clamping action by the springs 103. As the clips 83 and 84 continue their travel in opposite directions toward their stations the rounded side portions 111 of the cam-members 106 ride along the rails 124 and 125 with the movable jaws 102 released thereby and acting to clamp the yarn *y* against the fixed jaws 101.

Referring to Figs. 12 and 13, as the clips pass each other the cam-member 106 on the lower clip 84 is slid by its contact with the end of the rail 125 to not only cause the closing of the jaws, but also to move the shearing edge of the cam-member across that of the blade 116 to sever the length of yarn *y* leading between the clips. In this way the yarn trailing from the doffed bobbin is severed from the end in the yarn-guide 25 so that it may be carried to the tensioning drum in the manner as later explained.

The retriever-clip 83 which has clamped the end of the yarn *y* leading down from the yarn-guide 25 continues its travel to the left, as viewed in Figs. 12 and 13, and besides retrieving this end for attaching it to a newly donned bobbin *b*, it acts to return the yarn-guide 25 to initial winding position adjacent the head of the bobbin. The clip 83 is connected to slide the yarn-guide 25 by latching means shown in Fig. 13. The latching means may comprise a slide-bar 130 mounted on a laterally-extending rest or plate 131 which is fastened to the rearward side of the clip mounting 100. The slide-bar 130 is formed with longitudinally-extending slots 132 and 133 through which engage pins 134 and 135 projecting upwardly from the plate 131. Pivoted on the pin 134 above the slide-bar 130 is a pawl-like latch 136 formed with a shoulder 137 engageable with the edge of the vertical arm of the yarn-guide 25, see Fig. 12, to cause it to transmit the motion of the clip 83 to the guide for sliding it. The latch 136 carries a depending pin 138 at its end engaging in the slot 132 of the slide-bar 130 and adapted to slide in an offset, inclined cam-portion 140 of the slot to rock the latch to engage its shoulder 137 with the yarn-guide 25. A screw 141, see Fig. 13, adjustable through an upstanding lug 142 on the right-hand end of the slide-bar 130 is adapted to strike against an abutment 144 formed by a vertical shoulder of the framework, see Fig. 5, when the clip 83 reaches the end of its travel toward the right. When this contact takes place the slide-bar 130 will be slid to the left to rock the latch 136 and engage it with the yarn-guide 25 in the manner indicated in Fig. 12. Similar means are provided at the left-hand end of the slide-bar 130 for sliding it in the opposite direction to release the latch 136 from the yarn-guide 25. This means may comprise a screw 145 adjustable in an upstanding lug 146 on the slide-bar 130, see Fig. 12, the head of which is adapted to strike against the end wall of the casing 8 to shift the slide-bar to the right and release the latch 136 as shown in Fig. 13.

Referring to Figs. 5 and 13, the travel of the retriever-clip 83 to the left or toward the casing 8 also performs certain other functions as next explained. Beneath the head end of the bobbin is a loop-shaped wire bail 150 having one end formed as a pivot-stem 151 rotatable in a bearing in the base of the framework, see Fig. 5. A helical spring 152 surrounding the pivot-stem 151 of

the bail 150 normally maintains it rocked inwardly beneath the bobbin *b*. When, however, the yarn-guide 25 is returned to initial winding position by the travel of the clip 83 the clip 5 acts to swing the bail 150 outwardly into the position illustrated in the plan view, Fig. 13. This swinging motion of the clip is effected by the arcuate end portion 118 of the member 117 with one branch of the bail 150. The purpose of this 10 action is to assist in carrying the length of yarn *y* leading from the thread-guide 25 down to the clip 83 in under the prongs on the ferrule *f* carried by the bobbin *b*, see Fig. 5. The yarn 15 draws down to the clip 83 in back of the bobbin *b* as viewed in Fig. 5 and it is desirable that it be wrapped partly therearound as it slides along the barrel of the bobbin so that it will invariably be engaged under the fingers *p* on the ferrule *f*.

It has been stated that at the start of the winding a bunch containing a few coils of reserve yarn is wound on the bobbin *b* adjacent its head *h* with a shorter traverse than that imparted to the yarn by the yarn-guide 25. For this purpose an element 160, called a bunch-builder, is provided for holding the yarn to restrict its traverse by the guide 25. The bunch-building element 160 may take the form of a flat metal blade pivoted on a pin 161 and having a pin-and-slot connection with means for projecting it into position to engage the length of yarn between the guide 25 and the bobbin. The blade 160 is actuated by means not herein shown in detail but described in the continuing application referred to previously. Suffice it to explain, that as the yarn is carried back to engage it under the prongs *p* on the ferrule *f* it will ride across the edge of the bunch-building blade 160 so that when the blade is swung forward it will be engaged therewith to hold it from being traversed to the full extent by the yarn-guide 25. The blade 160 also cooperates with the bail 150 as indicated in Fig. 5 to cause the yarn leading down from the guide 25 to be wrapped partly around the barrel of the bobbin to insure its engagement under the prongs *p* on the ferrule *f*.

As the retriever-clip 83 reaches the end of its travel after attaching the yarn to the bobbin *b* the end of the yarn is released therefrom, being pulled out from the jaws of the clip as the bobbin starts to rotate, it being understood that the jaws 101 and 102 remain closed by the spring 105. When the clip 83 is again traveled to the right, however, at the start of winding the next bobbin the rounded side 111 of the cam-member 106 will ride off from the beveled end of the rail 124, see Fig. 14, and the opposite end of the cam-member will make contact with the end of an adjustable stud 126 held in a lug 127 on a depending portion of the tail-stock 15 to slide the cam-member to open the jaws of the clip.

Transfer-tail tensioning drum

Referring to Figs. 9 to 11, 16 and 17, the tensioning drum 170 which holds the end of the trailing yarn from the doffed bobbin is rotatably mounted in a recess or compartment 171 of the framework below the winding mechanism. The drum 170 is in the form of a sheet-metal cylinder supported by circular disks 172 and 173 at top and bottom of its interior. Projecting from the top of the cylinder 170 are a series of spaced teeth 175 inclined outwardly in the form of a

comb which acts to catch the yarn carried to the drum by the clip 84, see Figs. 16 and 17.

Yarn-detention gripper

In order to prevent the end of the yarn *y* from pulling out or becoming detached from the teeth 175, means are provided for gripping it at a point within the confines of the comb as shown in Figs. 16, 17 and 18. This detention means consists of a flap-like gripper 176 having ears at its upper end pivoted on a pin 177 held in a bearing member 178 fastened to the framework at 179. A helical spring 180 coiled around the pin 177 has one end held fast and its opposite end 181 engaged against the gripper, see Fig. 18, to normally rock it downwardly. The lower edge of the gripper 176 is adapted to engage against a resilient pad 182, constructed of sponge-rubber or the like, across the top of which the yarn is drawn as it is carried toward the right by the clip 84, see Fig. 5. The yarn *y* is drawn under the lower edge of the gripper 176 as the latter is swung upwardly during the travel of the clip 84 toward the right as shown in Fig. 16. Pivoted on the pin 177 in the bearing 178 is a depending plate 183 with which the clip 84 first makes contact to swing it against the gripper 176 and lift the latter for the passage of the clip thereunder. As the clip 84 approaches the end of its travel it passes beyond the gripper 176 and releases it to swing downwardly under the force of the spring 180 to pinch the yarn against the top of the pad 182 and resist its release from the drum 170. During the rotation of the drum 170 the fingers 175 of the comb will carry the yarn onto the periphery of the drum under the bail 198, as shown in Fig. 10, to hold it under tension. The drum 170 preferably is covered with a roughened material such as fabric to prevent the yarn from slipping thereon. Means are provided for releasing the end of the transfer-tail from the clip 84 after the latter has connected the yarn to the drum 170. For this purpose an abutment 126 at the right-hand end of the framework, see Fig. 5, has a forwardly-projecting finger positioned to engage the pin 121 and rotate the cylindrical cam 120 to cause it to rock the movable jaw 102 of the clip 84 away from the fixed jaw 101 in the manner previously explained. When the clip 84 is returned in the opposite direction for positioning it to pick up the transfer-tail from the next doffed bobbin it must pass the gripper 176 and this is provided for by an opening 184 in the side of the gripper, see Fig. 18. During the further travel of the clip 84 to the left it strikes against the suspended plate 183 as indicated in Fig. 18 to rock the latter outwardly and pass thereunder. Means are provided for releasing the cylindrical cam 120 from the movable jaw 102 as the clip moves to the left toward its station. For this purpose an abutment member 127', see Fig. 5, is adjustably mounted on the front of the framework by means of a screw 128 engaging through a slot in said member. The member 127' has a right-angular portion disposed to adapt it to strike against the end of the cam-member 106 on the clip 84 to slide the latter forwardly. The abutment member 127' also has a finger 129 projecting forwardly from its end in position to strike against the pin 124 to rotate the cam 120 for releasing it from the movable jaw 102. In this way the parts of the clip 84 are reset with its jaws open for engaging the yarn at the next forward travel of the clip.

Transfer-tail tensioning drum enclosure

As the drum 170 is rotated a bail 198, see Fig. 10, acts to frictionally hold the end of the transfer-tail against the drum to tension the yarn as it is drawn downwardly therealong during the descent of the bobbin in the reserve magazine. It will be understood that as the bobbins descend in the reserve magazine they draw the transfer-tails leading therefrom downwardly along the drum 170 so that upon the release of each bobbin from the magazine its respective transfer-tail is disengaged from the drum to adapt it to be caught and held for threading in the eye of the shuttle as later explained. The drum 170 is enclosed in a two-part cylindrical casing 189 comprising a rearward stationary section 190 fastened to a wall of the framework by screws 191, see Fig. 10. Attached to this part 190 of the casing 189 is a tubular bearing 192 enclosing a pin 193, see Fig. 9, on which is hinged the forward section 195. The section 195 is adapted to swing outwardly to open the casing 189 for inspection of the drum 170. A spring, not herein shown, or other suitable means may be provided for holding the section 195 of the casing 189 closed. The hinged section 195 of the casing 189 has bearing lugs 196, see Fig. 10, at top and bottom for rotatably mounting the roller-bail 198 in contact with the periphery of the drum to press the yarn thereagainst.

Drum-rotating means

The drum 170 is rotated by ratchet-mechanism located therebelow and normally actuated from the reciprocation of the loom-lay, see Figs. 10 and 11. The drum 170 is mounted for rotation on a vertical stud-shaft 200 journaled in a bearing in the base 201 of the compartment 171 of the framework of the winding means. The stud-shaft 200 projects through a bore in the lower disk 173 of the drum 170 and the disk 172 at the upper end of the drum is rotatable on a shouldered stud 202 projecting downwardly from a portion of the framework. Fastened against a boss or hub 203 on the under side of the lower disk 173 is a ratchet-disk 204 formed with relatively fine teeth on its periphery. The ratchet-disk 204 is rotatable on a bushing enclosing a shouldered portion of the stud-shaft 200 and is secured rotatively with the disk 173 of the drum by means of two pins 205 passing therethrough. A pawl 206 pivoted to a member 209 which is fast on the stud-shaft 200 is resiliently held in engagement with the teeth on the ratchet-disk 204 by means of a leaf-spring 210 fastened to the member 209 at 211. Mounted fast on the lower end of the stud-shaft 200 is a triangular-shaped arm 212 carrying a pin 213 at its pointed end to which is connected a helical spring 214 anchored to a pin 215 fast in the base 201 and projecting downwardly therefrom. The triangular arm 212 has a laterally-projecting pointed toe 216 at the opposite end from that connected to the spring 214. One edge of the toe 216 is adapted for engagement by a roller 220 on an oscillatable lever 221 which is pivoted on a pin 222 projecting below the base 201, see Fig. 11. The arcuately-shaped edge of the other arm of the lever 221 is positioned for engagement by a bunter 223 fastened to the top of the lay 2 of the loom. Through this arrangement the forward motion of the lay 2 causes the bunter 223 to strike the lever 221 and rock it on its pivot 222 to engage its roller 220 with the toe 216 and rock the triangular arm 212. As before noted,

the arm 212 is fast with the stud-shaft 200 and thereby causes the pawl-carrying member 209 to be rotated therewith to retract the pawl 208 rearwardly along the teeth of the ratchet-disk 204. Thus, when the bunter 223 recedes with the rearward stroke of the lay 2 the spring 214 will rotate the member 212 and advance the pawl 208 to rotate the ratchet-disk 204 and with it the drum 170 which turns in contra-clockwise direction as viewed in Fig. 10. This rotation is intermittent and continuous during the operation of the loom as effected by the reciprocation of the lay 2, the drum 170 being turned at a relatively slow speed since the pawl 208 is retracted only a few teeth at a time. To prevent reverse rotation of the drum 170 a brake-shoe 225, shown in Fig. 10, as pivoted on a stud 226, has an eccentric face engageable with the interior of the drum cylinder. A leaf-spring 227, shown in Fig. 10, tends to rock the brake-shoe 225 on its pivot so that normally it has substantially no braking effect against the interior of the drum cylinder when the latter is turned in the prescribed direction by the ratchet-means. However, any tendency for the drum 170 to turn in the opposite direction will cause the brake-shoe 225 to dog against its interior to resist such rotation.

Means for accelerating drum-rotation

It has been found of advantage to initially turn the drum 170 to a greater extent for insuring the attachment of the end of the transfer-tail thereto as the wound bobbin is held momentarily at the top of the reserve magazine. For this purpose a rockable lever 230 is pivoted at its upper end to a portion of the framework, see Figs. 8 and 9, to adapt its lower end to oscillate a horizontal lever 231 for actuating the ratchet-means described above. The lever 231 is pivoted on the stud-shaft 200 below the base 201 as shown in Figs. 10 and 11. The lever 231 carries a stud 232 projecting upwardly from its outer end with a convex-sided roller 233 journaled thereon and adapted to be engaged by the lower end of the lever 230. One side of the lever 231 is engageable with a lug 234 projecting upwardly from the triangular arm 212, see Fig. 9, whereby the rocking motion of the former will turn the latter to withdraw the pawl 208 a considerable distance rearwardly along the toothed periphery of the ratchet-disk 204.

The lever 230 is released by its actuating means at the end of the motion of the lever to the left as viewed in Fig. 9, whereupon a spring 228 connected at its lower end and anchored at 229 swings the lever in the opposite direction or toward the right. This latter movement of the lever 230 will release the lever 231 and allow the spring 214 to rotate the member 212 for advancing the pawl 208 to rotate the ratchet-disk 204. This action turns the ratchet-disk at a faster rate for rotating the drum 170 more rapidly to quickly draw the end of the yarn in the transfer-tail between the roller-bail 198 and the surface of the drum. In some instances it may be necessary to rotate the drum manually to wind on the end of a transfer-tail from a bobbin placed in the magazine and this may be accomplished by means of a finger-lever 235 shown in Fig. 10 as pivoted at 236 with its forward hooked end engaged with the roller 220 on the lever 221 which is operated by the bunter 223 on the lay of the loom.

The lever 230 is swung to the left as viewed in Fig. 9 by the traveling motion of the carriage 87

as it operates to traverse the clips 83 and 84 for the purpose previously explained. For this purpose the carriage 87 has a projecting stud 240 at its end adapted to strike against the end of a 5 slidable rod 241 carrying a collar 242 fastened thereto. The collar 242 is adapted to engage the edge of the lever 230 to rock the latter toward the left as viewed in Fig. 9 to stretch and load the spring 228. When the carriage 87 reverses its 10 motion to travel back in the opposite direction the lever 230 is released to swing toward the right and operate the ratchet-means in the manner as explained above. As shown in Fig. 9, the lever 230 is connected by an angular link 243 to a bell-crank lever 245 pivoted in a casing 246. The bell-crank lever 245 is rocked by the lever 230 for actuating detention means for controlling the entrance of doffed bobbins into the reserve-magazine at the opposite side of the casing 246.

Reserve-magazine for wound bobbins

Referring to Figs. 2, 3, 5, 6 and 7, the reserve-magazine for wound bobbins is similar in general to the construction used in conventional automatic looms. The present invention contemplates certain improvements for controlling the entrance of each bobbin into the reserve-magazine to detain it on a rest or shelf for an interval while its transfer-tail is being held and tensioned by the tensioning drum 170. The control means further provides for arresting the operation of the winding means when the magazine becomes filled with bobbins. As shown more particularly in Figs. 6 and 7, the reserve magazine, indicated generally by the reference character 250, is provided at the top with a hinged rest or shelf 251 which sustains each bobbin for an instant while its transfer-tail is held by the gripper 176 above the drum 170 and attached thereto by the accelerated rotation of the latter. The shelf 251 is hinged to the vertical wall of the casing 246, previously referred to, to adapt it to swing downwardly to release the bobbin and allow it to drop down in the magazine 250. The wound bobbins B are thus supplied to the reserve magazine 250 in overlying relationship at the rear of the usual filling fork with the lowermost bobbin in position to be transferred to the shuttle by the transfer-hammer 252 shown in Fig. 2.

Bobbin-detaining means

The bobbin-detention shelf 251 is maintained raised in horizontal position by means of a lever 253 pivotally supported on a shaft 254 within the casing 246 and formed with a curved finger 255 projecting through an opening in the forward wall of the casing with its end engaging the under side of the shelf, see Fig. 7. The lever 253 is held in the position shown in Fig. 7 with the shelf 251 raised by means of a spring 249 on its shaft 254, see Fig. 9. After a relatively short interval the doffed bobbin B is released from the shelf 251 by the action of the mechanism contained in the casing 246, see Fig. 9, and previously referred to. The three-armed bell-crank lever 245, previously mentioned, has one of its arms 256 carrying a pin 257 engageable through a slot 258 in a vertical link 259. The upper end of the link 259 is pivotally connected to an arm 260 reaching outwardly from the lever 253 which supports the shelf 251. When the drum-accelerating lever 230 is swung to the left by the travel of the carriage 87 the connecting link 243 will rock the bell-crank lever 245 to cause its arm 256 to raise the vertical link 259 and thereby rock the lever 253 to withdraw its curved finger 255 from under the shelf 251.

The shelf 251 is therewith allowed to swing downwardly to release the bobbin held thereon and cause it to drop by gravity in the magazine 250. Clamping means, to be described in the continuing application referred to above, are provided for engaging the heads of the bobbins to hold them from turning in the magazine, the clamps being released automatically to permit the bobbins to slide down in the magazine as each lowermost one is transferred to the shuttle of the loom.

Bobbin-leveling shelf

To prevent the bobbin released from the tilted detention shelf or rest 251 from becoming carried as it drops in the magazine 250 a second rest or shelf 265 is arranged below the shelf 251, see Figs. 6 and 7. The shelf 265 is hinged to the wall of the casing 246 at 266 and is counterbalanced by a weighted arm 267 projecting through an opening in the wall and adapted to normally maintain the rest in horizontal relationship. When the bobbin drops on the shelf 265 it will overbalance the weighted arm 267 and cause the shelf to swing downwardly and release the bobbin to drop toward the bottom of the magazine while leveling and positioning it for proper transfer to the shuttle.

Full-magazine control for stopping winding means

The bell-crank lever 245 which operates the lever 253 to release the detention rest or shelf 251 also has another function, namely, to arrest the operation of the winding means when the reserve magazine becomes filled with wound bobbins. The stopping mechanism for the winding means may be either mechanically or electrically operated and as herein shown a so-called "micro-switch" 275 is employed, see Fig. 9, for opening the circuit to the electric motor 9 shown in Fig. 4. The switch contains contact members for closing the circuit and by actuating it the circuit is opened in the usual way. For this purpose a rockable arm 276 is connected to the upright arm 277 of the bell-crank lever 245 with its forward end formed with an arcuate cam-piece 278. The cam-piece 278 is adapted to ride against a roller 279 on an arm 280 projecting from the side of the switch 275. The arm 276 is formed with a longitudinal slot 281 slidably engaged by a pin 282 projecting from the vertical link 259 which controls the position of the bobbin-detention shelf.

Normally, when the link 259 is raised by the rocking of the bell-crank lever 245 to release the lever 253 from the shelf 251 the arm 276 will be slid to the right as viewed in Fig. 9 so that its cam-piece 278 will clear the roller 279 connected to the switch 275. Consequently, the circuit will remain closed to supply current to the motor 9. When, however, the magazine 250 becomes filled with bobbins and the last-entered one holds the shelf 251 depressed the above-described mechanism will function to operate the switch 275 and open the circuit to interrupt the flow of current to the motor, thereby arresting the operation of the winding means. This last described action is caused by the link 259 being lifted and held raised through its connection at 260 with the shelf 251 when the latter remains depressed by a bobbin resting thereon. As the bell-crank lever 245 returns to its rest position shown in Fig. 9 the arm 276 is slid to the left, and due to said arm being held in raised position by the link 259, as permitted by its pin-and-slot connection with the

lever 245 at 281, 282, the cam-piece 278 on the arm engages with the roller 279 on the switch-lever 280 to actuate the switch 275 and open the circuit to the driving motor 9. The switch 275 is thereby operated to open the circuit to the motor and arrest the operation of the winding means until a bobbin has been transferred from the magazine 250 and the bobbins thereabove lowered to release the shelf 251. As the shelf 251 is released and the parts restored to first position the link 259 drops to the position shown in Fig. 9 and thereby rocks the arm 276 downwardly to remove the cam-piece 278 from the roller 279 to permit the switch 275 to operate to close the circuit to the motor and restart the winding means. Means are also provided for releasing the clamping means in the magazine to free the bobbins so that they cannot jam therein and prevent release of the bobbin detained on the shelf 251. Such means are shown at the right in Fig. 9.

Transfer-tail clamping and positioning means

The operation of the various mechanisms described above is continuous with the operation of the loom and when the feeler indicates that the filling in the running shuttle is nearly exhausted the transfer of a fresh bobbin to the shuttle is accomplished in the same manner as performed in conventional automatic looms. The present invention, however, provides new and improved clamping means for holding the transfer-tail from the bobbin in transferring position and clamping it to carry it into alignment with the eye of the shuttle for threading it therethrough. This improved means is illustrated in Figs. 7, 9, 20 and 21. Suffice it to state herein that it functions in the manner next explained. The end of the transfer-tail from the bobbin B in transferring position is held by a finger 285, shown in Figs. 20 and 21, which cooperates with a reciprocable yarn-clamp 286, the finger acting to locate the yarn for entering it between the jaws of the clamp. The jaws of the clamp are open when the slack end of the yarn is drawn thereinto while the bobbin is being transferred into the shuttle. The clamp 286 is slideable on a horizontal rod 288 and normally held in the position illustrated in Fig. 20 against the tension of a spring 289 surrounding the rod. For this purpose a latching- or cocking-means comprises a lever 290 pivoted to a rockable arm 291 on the side of the clamp 286. The lever 290 is pivoted at 292 on a support extending from casing 246 and carries a pin 293 engageable in a notch 294 in a latching-lever 295 pivoted on a stud 296. Carried at the end of a rockable rod 297 is an arm 298 connected by a link 299 to the curved free end of the latching-lever 295. The rod 297 is connected to be rocked by the transfer-hammer 252, previously mentioned, to cause it to rotate the arm 298 and depress the locking lever 295 to release the lever 290. By this unlatching action the clamp 286 is released to slide forward on the rod 288 under the force of the spring 289. As the clamp 286 starts to slide a movable jaw 300 is swung against its forward end to seize the end of the yarn entered therebetween. This action takes place as a bobbin is being transferred into the shuttle shown in Fig. 2. This latter view also illustrates a lever 302 which is rocked by the transfer-hammer 252 and through a link 303 connected to an arm 304 rocks the rod 297, previously referred to, which controls the latching-means shown in Fig. 20. The transfer-tail clamp 286 is thus slid into

position by the spring 289 to aline the yarn held therein with the eye of the shuttle for threading it therethrough. As the clamp 286 is slid to the position shown in Fig. 21 a roller 305 carried thereby travels along an arcuate track 306 to cause it to rock a lever 307 and depress a finger 308. The finger 308 is thus carried down into position to be struck by a bunter 310 on the lay 2, see Figs. 2 and 6, at the next succeeding return stroke of the lay whereby to restore the clamp to first position and cause it to be latched against the pressure of its spring 289. It will be understood that the sliding yarn-clamp 286 first alines the transfer-tail with the eye of the shuttle at the start of the picking motion and when the lay 2 reaches front center the transfer-tail is forced under two stationary hooks and held in position to allow the temple cutter, not shown, to cut the end at the selvage edge. After the end has been severed it is dropped into a thread-clearer of usual construction, but not herein shown, and the clearer takes up the severed end, pulls it out of the yarn-clamp, as the latter is returned to open position to receive the transfer-tail on the next bobbin to be transferred. With the present improved construction of the transfer-tail clamping means the yarn is alined more accurately with the eye of the shuttle at the start of the picking motion and the bobbin placed into the shuttle before the end is clamped tight. It will be understood that as a new bobbin B is transferred into the shuttle it will force the spent bobbin out through the bottom thereof and a usual type thread-cutter, not herein shown, is provided to cut the trailing end from the bobbin which has been ejected. As the ejected bobbin leaves the shuttle it descends into a chute C, see Fig. 1, which directs it into the stripper S for removing the residue of yarn remaining thereon, the denuded bobbin being delivered into a tray or receptor R at the bottom of the stripper as explained in the pending application, Serial No. 112,362, filed August 25, 1949. A conveyor-belt 315 passing around an upper pulley 316 located adjacent the empty bobbin-magazine 20 and a lower pulley 317 above the receptor R has its opposite lengths guided at an intermediate point by two flanged pulleys 318. The conveyor-belt 315 is driven continuously from the loom by means shown in the pending patent application referred to above. The conveyor-belt 315 may carry one or more permanent magnets 319 suspended therefrom for picking up the empty bobbins b' from the receptor R by attaching itself to the metal rings r on the head of the bobbin as described in the application last referred to. As illustrated in Fig. 1, the empty bobbin b' is conveyed upwardly and carried around the upper pulley 316 for releasing it to enter the trough 19 at the top of the magazine 20. Referring to Fig. 3, as the empty bobbin b' passes across the pulley 316 its tip end slides under an inclined crossbar 320 projecting from the side of a guideplate 321 fast on the framework. The crossbar 320 acts to hold the tip end of the bobbin b' down to cause the rings r on its head to be released from the magnet 319 so that it will slide along the trough 19 into position to drop down in the chutes 21 and 22. In this way each ejected bobbin is conditioned for winding by stripping the residue of yarn therefrom and thereafter conveyed upwardly to deposit it in the magazine 20 from which it is delivered for donning on the winding means.

It will be observed from the above specification that the present invention involves an entirely

new conception in the method of preparing and supplying filling to an automatic loom. The apparatus operates in a complete cycle to wind filling bobbins, doff them from the winding means, ready them for transfer to the loom-shuttle, remove the residue of yarn therefrom as the bobbins are ejected from the shuttle, convey the empty bobbins to a magazine at the winding means, and don them in connection with the winding spindle. As before noted, the invention completely eliminates the requirement for a winding room, eliminates manual operations for handling and transporting the bobbins, increases the efficiency of the loom by realizing higher speeds, and does away with the use of pin-boards, weighing scales, storage racks, and other appurtenances. It also avoids the use of colors for identifying the yarn on the bobbins and minimizes the chances of mixed filling in the loom besides tending to preserve the high quality of the yarn.

Method of operation of the complete apparatus

As a preferred method of operation of the complete apparatus its units are so adjusted that seven full bobbins are normally in reserve in the full bobbin magazine when the winding means is functioning. This serves as a safety factor in the event of winding stoppage so as to allow sufficient time for piecing up or other manual operations before stoppage of the loom for lack of filling. The winding means may produce wound bobbins at a rate approximately ten to twenty percent faster than the filling is used by the loom. This practice requires that a maximum of eleven bobbins be maintained in the loom as follows: seven in the reserve-magazine, one in the shuttle, one in the stripper, one in the empty bobbin-magazine, and one in winding position. In this way maximum production of the loom is maintained to secure the advantages set out above.

While the invention is herein shown and described as embodied in a preferred form of construction of the cooperating units, it is to be understood that modifications may be made in the structure and arrangement of the parts of the mechanism without departing from the spirit or scope of the invention. Therefore, without limiting ourselves in this respect, we claim:

1. In combination, means for winding filling-bobbins and supplying them to the shuttle of a loom embodying filling-changing mechanism, means for donning empty bobbins on said winding means, means for doffing wound bobbins from the winding means and furnishing them to the filling-changing mechanism of the loom, means for receiving spent bobbins ejected from the loom-shuttle by the filling-changing mechanism and stripping the residue of yarn therefrom, and means for conveying the stripped or denuded bobbins back to the winding means for donning them in operative connection therewith.

2. In combination, means for winding filling-bobbins in a loom provided with a magazine for wound bobbins and a shuttle for receiving the bobbins, means for donning empty bobbins in connection with said winding means, means for automatically doffing wound bobbins therefrom, means for delivering the wound bobbins to the magazine of the loom, means for transferring a bobbin from the loom-magazine to the shuttle of the loom and ejecting a spent bobbin therefrom, means for holding spent bobbins ejected from the shuttle and removing the yarn there-

from, and means for conveying the denuded or empty bobbins back to the winding means for donning them thereon.

3. In combination with a loom embodying filling-changing mechanism and a shuttle for carrying filling bobbins, means for continuously winding bobbins and furnishing them to the filling-changing mechanism thereof comprising a rotary winding spindle, means for donning empty bobbins in driving connection with said winding spindle, means for doffing wound bobbins from the winding spindle, means for drawing off a length of yarn from a doffed bobbin, means for holding the end of said length of yarn, and means for transferring a bobbin into the shuttle of the loom and automatically threading the shuttle with the yarn trailing from said bobbin.

4. In combination with the filling-changing mechanism of a loom including a filling-feeler and a shuttle for containing filling bobbins, winding means built into the structure of the loom, means for automatically operating said winding means to continuously wind yarn into filling bobbins, automatically-operated means to doff wound bobbins from the winding means, and means to transfer the wound bobbins to the shuttle as called for by the filling-feeler of the loom.

5. In a loom having a shuttle for carrying filling bobbins, the combination of winding means built into the structure of the loom, means for donning empty bobbins in connection with said winding means, means for doffing wound bobbins from the winding means, means for grasping the end of the yarn on a wound bobbin and drawing off a transfer-tail therefrom, means for holding the end of said transfer-tail, and means for transferring the wound bobbin to the shuttle of the loom and threading the shuttle with the yarn in the transfer-tail.

6. In a loom having filling-changing mechanism and a shuttle for filling bobbins, winding means embodied in the structure of the loom, means for automatically donning empty bobbins on the winding means, means for doffing wound bobbins from the winding means, means for transferring wound bobbins to the shuttle of the loom, means for receiving spent bobbins ejected from the shuttle and removing the residue of yarn therefrom, and means for returning the denuded bobbins to the donning means of the winding means.

7. In a loom having a shuttle for filling bobbins, means for winding filling bobbins, means for donning empty bobbins on said winding means, means for doffing wound bobbins from the winding means, means for engaging the end of the yarn on a wound bobbin and drawing off a length therefrom, means for holding the end of said length of yarn, and means for transferring a doffed bobbin to the shuttle and ejecting the spent bobbin therefrom.

8. In a loom having filling-changing mechanism and a shuttle for filling bobbins, means for winding filling yarn on bobbins, means for doffing wound bobbins, means for seizing the end of the yarn on a wound bobbin and drawing off a length therefrom, means for tensioning the length of yarn drawn off by the seizing means, means for transferring the wound bobbin to the shuttle of the loom, and means for threading the yarn from the bobbin into the eye of the shuttle.

9. In combination with the filling-changing

mechanism and the shuttle of an automatic loom, bobbin-winding means in the loom, a magazine for empty bobbins, donning means for taking the empty bobbins from the magazine and applying them to the winding means, means for doffing wound bobbins from the winding means, means for transferring a wound bobbin to the shuttle of the loom and ejecting a spent bobbin therefrom, a stripper for receiving the spent bobbins and removing the residue of yarn therefrom, and a conveyor for taking the denuded bobbins from the stripper and conveying them back to the magazine for empty bobbins.

10. In a loom embodying filling-changing mechanism and a shuttle for filling bobbins, a rotary winding spindle, means for rotating said spindle, means for donning empty bobbins in connection with said spindle, means for traversing yarn to wind it on the bobbins, means for automatically doffing wound bobbins from the winding spindle, a magazine for holding wound bobbins in reserve for delivery to the filling-changing mechanism of the loom, means for transferring bobbins from the magazine to the shuttle of the loom, means for receiving spent bobbins ejected from the shuttle, means for stripping the residue of yarn from said spent bobbins, and means for returning the stripped bobbins to the donning means in a continuous cycle.

11. In a loom having filling-changing mechanism and a shuttle for weft bobbins, means for winding weft bobbins in the loom, means for doffing wound bobbins from the winding means, a magazine for holding a reserve supply of wound bobbins, means for transferring bobbins from the reserve magazine to the shuttle of the loom, and means operative by the bobbins in the reserve magazine for arresting the operation of the winding means when said magazine becomes filled with bobbins.

12. In a loom having filling-changing mechanism and a shuttle for filling bobbins, means for winding filling bobbins in the loom, means for denning empty bobbins in connection with the winding means, means for doffing wound bobbins from the winding means, a reserve magazine for holding wound bobbins doffed from the winding means, means to transfer said wound bobbins to the shuttle of the loom, stopping means for arresting the operation of the winding means, and means actuated by a full supply of bobbins in the reserve magazine for operating the stopping means to arrest the operation of the winding means.

13. In a loom embodying filling-changing mechanism and a magazine for holding a reserve supply of wound filling bobbins, means for winding filling bobbins in the loom, means for doffing wound bobbins from the winding means and supplying them to the loom-magazine, means operated automatically to arrest the operation of the winding means when said magazine becomes filled with bobbins, and means for restarting the operation of the winding means when the supply of bobbins in said magazine becomes depleted.

14. In a loom, the combination with the filling-changing mechanism thereof and a shuttle for containing filling bobbins, means for winding filling-bobbins in the loom, a magazine in the loom for holding a reserve supply of wound bobbins, means for doffing wound bobbins from the winding means and supplying them to the loom-magazine, means for arresting the operation of the winding means when said magazine becomes filled with bobbins, and means for restarting the

operation of the winding means after a bobbin has been transferred from the magazine to the loom-shuttle by the filling-changing mechanism.

15. In a loom embodying filling-changing mechanism and a shuttle for wound filling bobbins, means for winding filling bobbins in the loom, means for doffing wound bobbins from the winding means, a magazine for receiving the wound bobbins doffed from the winding means, means for transferring bobbins from said magazine to the shuttle of the loom, stopping means for arresting the operation of the winding means, means engageable by the doffed bobbins as they are supplied to the magazine, and means controlled by said last-named means to actuate the stopping means for the winding means when the magazine becomes filled with bobbins and to restart the operation of the winding means when the supply of bobbins in the magazine is depleted.

16. In combination with the filling-changing mechanism of a loom including a magazine for reserve bobbins and a shuttle for carrying filling bobbins, means for winding filling-bobbins in the loom, means for doffing wound bobbins from the winding means to deliver them to the magazine of the loom, means for seizing the yarn trailing from a doffed bobbin and drawing it off therefrom, a rotary drum, means for carrying the seized end of the yarn to said drum to cause a length thereof to be held thereon, and means for transferring a wound bobbin from the magazine to the shuttle of the loom while holding the end of the yarn therefrom to cause the shuttle to be threaded with the yarn.

17. In combination with the filling-changing mechanism of a loom and a shuttle for carrying filling bobbins, means for winding filling-bobbins in the loom, means for donning empty bobbins on the winding means, means for doffing wound bobbins from the winding means, a clip for seizing the end of yarn trailing from a doffed bobbin and severing it from the supply yarn, a rotary drum, means for actuating the clip to carry the seized end of the yarn from the doffed bobbin to the drum to cause it to be held thereon, means for transferring the doffed bobbin to the shuttle of the loom, and means for taking the end of the yarn from the drum and shifting it into position to thread the shuttle therewith.

18. In a loom embodying filling-changing mechanism including a magazine for reserve bobbins and a shuttle for containing filling bobbins, means for winding filling bobbins in the loom, means for doffing wound bobbins from the winding means and supplying them to the magazine, means for transferring bobbins from the magazine to the shuttle of the loom, a clip for seizing the end of the yarn trailing from a doffed bobbin, a rotary drum, a ratchet for rotating said drum, means operated from a going member of the loom to actuate the ratchet, means to operate the clip to carry the yarn seized therein and connect it to the rotary drum to hold it thereon, said drum acting to hold the ends of yarn from the several bobbins in the magazine, and means operative during the transfer of a bobbin from the magazine to the shuttle to grip the yarn and hold it for threading through the eye of the shuttle.

19. In a loom embodying filling-changing mechanism, a magazine for holding a reserve supply of filling bobbins and a shuttle for receiving said bobbins, the combination therewith of means for winding filling-bobbins in the loom, means for doffing wound bobbins from the wind-

ing means and delivering them to the magazine, a rotary drum, means actuated by the operation of the loom to rotate the drum intermittently, a clip for seizing the end of the yarn trailing from a bobbin as it is doffed from the winding means and delivered to the magazine, means for operating said clip to carry the end of the yarn to the drum to cause it to be held thereon to provide a transfer-tail, said drum acting to hold under tension the several transfer tails from the bobbins in the magazine, and means to transfer the bobbins individually from the magazine into the shuttle of the loom.

20. In a loom in combination with the filling-changing mechanism and shuttle thereof, a magazine for holding a supply of filling bobbins in reserve, means for transferring the bobbins individually from the magazine to the shuttle of the loom, means in the loom for winding filling-bobbins and delivering them directly to the reserve magazine, stopping means for arresting the operation of the winding means, electrically-operated means for actuating the stopping means, a switch in circuit with said electrical means, and control means actuated by a bobbin entering the magazine to completely fill it with bobbins, said control means operating to close the switch to actuate the stopping mechanism for the winding means.

21. In combination, means for winding filling bobbins for a loom having filling-changing mechanism and a shuttle, means for donning empty bobbins on said winding means, means for doffing wound bobbins from the winding means, means for supplying said wound bobbins to the filling-changing mechanism of the loom, means for taking spent bobbins ejected from the shuttle and stripping the residue of yarn therefrom, and means for returning said stripped or denuded bobbins to the winding means for repeatedly winding filling thereon.

22. In combination, means for winding filling bobbins, means for donning empty bobbins on said winding means, means for doffing wound bobbins from the winding means and supplying them to the filling-changing mechanism of a loom, means for taking spent bobbins ejected from said loom and stripping the residue of yarn therefrom, and means for returning the stripped or denuded bobbins to the donning means for resupplying them to the winding means.

23. In combination with the filling-changing mechanism of a loom, its shuttle and a filling-feeler for testing the filling in said shuttle, a bobbin-winder, means for automatically operating said bobbin-winder, means to don empty bobbins on said winder, means to doff wound bobbins from the winder, and means to transfer the wound bobbins to the shuttle as called for by the filling-feeler of the loom.

24. In combination with an automatic loom having filling-changing mechanism and a shuttle, means for winding filling bobbins, means for donning empty bobbins on said winding means, means for doffing wound bobbins from the winding means and supplying them to the filling-changing mechanism of the loom, means for taking spent bobbins ejected from the loom-shuttle and stripping the residue of yarn therefrom, and means for returning said stripped bobbins to the winding means for donning them in operative connection therewith.

25. In combination with a winding machine for supplying filling bobbins to a loom, means for

25

donning empty bobbins on said winding machine, means for doffing wound bobbins from the winding machine, means for supplying said wound bobbins for weaving in the loom, means to take spent bobbins from the loom and strip the residue of yarn therefrom, and means for returning the stripped or denuded bobbins to the winding machine for donning them thereon.

26. In a loom having filling-changing mechanism and a shuttle, the combination therewith of means for winding filling bobbins for said shuttle, means for donning empty bobbins on the winding means, means for doffing wound bobbins from the winding means, means for transferring said wound bobbins to the shuttle of the loom, means for taking spent bobbins ejected from the shuttle and removing the residue of yarn therefrom, and means for returning the denuded bobbins to the donning means for repeated use by the winding means.

27. In combination with a loom having filling-changing mechanism and a shuttle, means for winding filling yarn on bobbins, means for doffing wound bobbins therefrom, means for seizing the end of the yarn leading from a wound bobbin, means for tensioning said length of yarn, means for transferring the wound bobbins to the shuttle of the loom, and means for threading the shuttle with said length of yarn held under tension.

28. Means for supplying wound bobbins to the filling-changing mechanism of a loom comprising means for winding the filling bobbins, means for donning empty bobbins in connection with the winding means, means for doffing wound bobbins from the winding means, means for holding a number of wound bobbins in reserve, means to transfer said wound bobbins individually to the shuttle of the loom, stopping means for arresting the operation of the winding means, and means for actuating the stopping means when the wound bobbins held in reserve exceed a certain number.

29. For an automatic loom embodying filling-changing mechanism and a shuttle for filling bobbins, means for winding filling on empty bobbins, means for doffing wound bobbins from the winding means, means for holding a reserve supply

26

of wound bobbins, means for transferring bobbins from the reserve supply to the shuttle of the loom, and means operative when the bobbins held in reserve exceed a certain number for arresting the operation of the winding means until one or more of the reserve bobbins has been delivered to the shuttle.

30. For a loom embodying filling-changing mechanism and a shuttle for receiving wound filling bobbins, means for winding filling on empty bobbins, means for doffing wound bobbins from the winding means, means for holding a supply of wound bobbins in reserve, means for arresting the operation of the winding means when the supply of reserve bobbins exceeds a definite number, and means for restarting the operation of the winding machine when the supply of reserve bobbins becomes depleted.

31. In combination with an automatic loom having filling-changing mechanism and a shuttle, means for winding filling bobbins, means for donning empty bobbins on said winding means, means for doffing wound bobbins from the winding means and supplying them to the filling-changing mechanism of the loom, and means for taking spent bobbins ejected from the loom-shuttle and stripping the residue of yarn therefrom.

32. In combination with an automatic loom having filling-changing mechanism and a shuttle, means for winding filling bobbins, means for donning empty bobbins on said winding means, means for doffing wound bobbins from the winding means and supplying them to the filling-changing mechanism of the loom, and means for returning the bobbins ejected from the loom-shuttle to the winding means for donning them in operative connection therewith.

WILLIAM V. GOODHUE.
